UNITED STATES PATENT OFFICE.

JEROME REDDING, OF MALDEN, ASSIGNOR TO HIMSELF AND HARVEY REDDING, OF EVERETT, MASSACHUSETTS.

ELECTRIC GAS-LIGHTING.

SPECIFICATION forming part of Letters Patent No. 242,693, dated June 7, 1881.

Application filed February 21, 1881. (No model.)

To all whom it may concern:

Be it known that I, JEROME REDDING, of Malden, in the county of Middlesex and State of Massachusetts, have invented certain Im- 5 provements in Electric Gas-Lighting, of which the following is a specification.

This invention relates to the method of electric gas-lighting in which a piece of platinum located over the tip of a gas-burner within 10 in the space occupied by the flame is made red-hot or incandescent by electricity, and so caused to ignite the gas.

Heretofore it has been considered necessary in some apparatus to make the platinum in- 15 candescent wholly by electricity, and the method has therefore been found expensive and comparatively difficult to carry out successfully when a large number of burners are to be simultaneously lighted, for the following rea- 20 sons: First, if battery-currents are employed to heat the platinum, a very large and expensive battery is required to obtain sufficient strength of current to sufficiently heat the platinum strips or wires of a large number of 25 burners; secondly, if currents generated by a dynamo-electric machine are employed, much power is required to generate a current of suffi- 30 cient strength, and there is danger of melting and destroying the platinum strips or wires by the combined action of the current and the gas-flame, if the current is maintained too long after the gas is lighted.

My invention has for its object to provide a method of heating the platinum which shall be 35 free from the objections and difficulties above named; and to this end it consists in, first, an electric gas-lighting system having a gas-burner, a platinum wire located in an electric circuit, and a slip or piece of platinum projecting 40 from said wire into the space occupied by the gas-flame, so that said platinum may be heated by electricity to a point short of incandescence and be rendered incandescent by and capable of igniting the gas issuing unignited from the 45 burner.

My invention also consists in the employ- 50 ment of an electro-magnet having a neutral armature for operating the gas-cock with a step-by-step motion in turning on or shutting off the gas, and a polarized armature to arrest

the turning of the gas-cock when the same is entirely opened or entirely closed. The gas-cock has a ratchet-wheel, and the neutral armature is connected to a bell-crank lever carrying a dog engaging with the ratchet-wheel and moving the same the distance of one tooth whenever the neutral armature is attracted. The polarized armature is adapted to assume either of two positions, according to the polarity of the exciting-currents. When in one position it arrests a pin on the ratchet when the cock is entirely open, and when in the other position it arrests another pin on the ratchet when the cock is entirely closed. An operator at a central station is therefore enabled to insure the complete opening or closing of all the gas-cocks in the circuit by giving a greater number of impulses of one polarity than is required to fully open or fully close the cocks, and thus provide against an occasional failure of one of the dogs to operate its ratchet, the polarized armature preventing the cocks from being moved too far by the extra number of impulses, in case such failure to operate does not occur. 75

Of the accompanying drawings, forming a part of this specification, Figure 1 represents an elevation of a gas-cock embodying my invention, showing a side view of the cock-operating ratchet, and Fig. 2 represents an edge 80 view of said ratchet.

The same letters of reference relate to the same parts in both figures.

In the drawings, *a* represents the burner, and *b* represents a piece of platinum or platinum sponge to ignite the gas, the platinum being located wholly or in part in an electric circuit. The platinum *b* may be a single piece in the form of wire arranged directly in the circuit, if desired; but I prefer to make it in two parts, 85 as shown, one part being the wire 1, located directly in the circuit and outside the space occupied by the flame, and the other being a slip, 2, attached to the wire 1 and projecting laterally therefrom into the space occupied by 90 the flame, and therefore out of the circuit. By this latter arrangement that portion of the platinum through which the current flows is entirely outside of the flame and not liable to be burned off. Ordinary platinum may be em- 100

ployed, or platinum sponge, or the alloy known as "platinum-iridium," or, in fact, any metal or alloy which is capable of being heated to redness in the manner described. The platinum, 5 as before stated, is preferably about an inch and one-half from the tip of the burner.

c represents the ratchet on the arbor of the gas-cock *a*.

d represents the electro-magnet.

10 *e* represents the neutral armature attached to a bell-crank lever, *f*, which is pivoted at *i* to a fixed support.

15 *j* represents the dog, which is pivoted to the lever *f* and engages with the teeth of the ratchet.

20 *k* represents a polarized armature arranged to vibrate between the lateral poles *l l'* of the electro-magnet, and provided with arms or bifurcations *k' k''* at its upper end, as shown in Fig. 2, so as to project on both sides of the ratchet.

25 *m m'* represent pins located at diametrically opposite points on the ratchet, and projecting respectively from the outer and inner sides of same.

When the polarized armature is attracted by the pole *l* of the electro-magnet its arm *k'* is in position to arrest the pin *m* on the outer side of the ratchet, and when the polarized armature is attracted by the pole *l'* its arm *k''* is in position to arrest the pin *m'* on the opposite side of the ratchet. When the pin *m* reaches the arm *k'* the cock is supposed to be fully closed, and cannot be opened until the polarity 35 of the currents exciting the magnet *d* is reversed.

When the gas is to be turned on, the operator at a central station reverses the polarity of the exciting-currents and sends a sufficient 40 number of impulses to bring the pin *m'* to the arm *k''* of the polarized armature, each impulse operating the dog *j* and rotating the ratchet *c* the distance of one tooth; but as the dog is liable to occasionally fail to engage a tooth of 45 the ratchet it is obvious that the operator may send a greater number of impulses without moving any of the cocks too far, thus insuring

the full opening of all the cocks and the bringing of all the cocks to unison.

When the gas is to be turned off the polarity of the exciting currents is again reversed and the operation repeated until the ratchets are arrested by the arm *k'* of the polarized armature. 50

I do not limit myself to the employment of a polarized armature as a unison device or stop for the gas-cocks, as other mechanism or devices operated electro-mechanically from a central station may be employed to secure the unison of all the gas-cocks without departing 60 from the spirit of my invention.

Having thus described my invention, I claim—

1. In an electric gas-lighting system, the combination of a gas-burner, a platinum wire 65 located in an electric circuit, and a slip or piece of platinum projecting from said wire into the space occupied by the flame, substantially as and for the purpose described.

2. In an electric gas-lighting system, the combination of a gas-cock provided with a ratchet, an electro-magnet having a neutral armature to operate the ratchet through suitable intermediate mechanism, and a polarized armature adapted to arrest the cock either when 75 fully opened or fully closed, as and for the purpose set forth.

3. In an electric gas-lighting system, a gas-cock having a ratchet-wheel on its arbor operated step by step from a distant station, in 80 combination with a unison-stop composed of an electrically-operated forked lever, and pins on the ratchet-wheel to arrest the rotation of the cock when the same is fully opened and fully closed, as and for the purpose specified. 85

In testimony whereof I have signed my name to this specification, in the presence of two subscribing witnesses, this 16th day of February, A. D. 1881.

JEROME REDDING.
